UNITED STATES PATENT OFFICE

PAUL A. JOHNSON, OF GRAND HAVEN, MICHIGAN, ASSIGNOR OF ONE-HALF TO ALVIN E. JACOBSON, OF GRAND HAVEN, MICHIGAN

TOILET-SEAT HINGE

Application filed April 9, 1928. Serial No. 268,768.

This invention relates to hinges particularly adapted for use with toilet seats and covers therefor. It is an object and purpose of the present invention to construct a very simple, 5 practical and economical hinge structure which is adapted to be used in hingedly connecting a toilet seat to the bowl and also hingedly mount a cover over and with respect to the seat.

10 An understanding of the invention and the preferred structural embodiment thereof may be had from the following description taken in connection with the accompanying drawing, in which,

15 Fig. 1 is a fragmentary rear elevation illustrating the use of a pair of said hinges in conjunction with a toilet seat and cover.

Fig. 2 is a fragmentary side elevation thereof, and

20 Fig. 3 illustrates in perspective the several parts of the hinge.

Like reference characters refer to like parts in the different figures of the drawing.

The bowl 1 is provided with a rearwardly 25 extending horizontal ledge 2 at its rear side and upper end through which, at two spaced apart points, openings are made for the passage of bolts 3 threaded at their lower ends. Said bolts 3 at their upper ends are equipped 30 with enlarged heads which have a lower flange 4 to bear against the upper side of the ledge 2 above which the head 5 is located. Heads 5 at their outer sides are formed with horizontal cylindrical openings 6 which extend 35 nearly through said heads 5, but which are closed at their inner ends.

When the bolts 3 are passed downwardly 40 through the openings in the ledge 2, the flanges 4 bear against the upper side of said ledge and are drawn tightly thereagainst by a nut 7 screwed on to the lower end of each bolt 3 and against a washer 8 which is interposed between the nut and the lower side of said ledge.

45 A hinge member is designed to be pivotally connected with each of the heads 5. This hinge member includes at its lower end a cylindrical pin 9 which seats in the opening 6 in each head 5. From the outer end of the 50 pin 9 the hinge member extends upwardly

and outwardly at an angle to the vertical, making a section 10 which at its upper end is turned to extend forward in a horizontal plane, making a section 11, and terminates at its front end in an upwardly extending head 12 which, at its inner side, is provided with a horizontal cylindrical opening 13. The openings 13, like the openings 6, extend only part way through the heads in which they are made.

55 A cylindrical pin having an end portion 14 is adapted to be received in each opening 13. The pin carries a collar 15 which bears against the inner side of each head 12 and is thence extended inwardly in a longer section 16, the two sections 16 of the pin being inserted in a toilet seat cover 17 at opposite side edges and at the rear end thereof. The hinge member sections 10 and 11 lie respectively back and above the seat 18, screws passing through the sections 10 into the rear edge of said seat and similar screws 12 passing through the horizontal sections 11 into the upper side of the seat adjacent its rear end. It is evident that the seat and cover may be assembled with the 60 bowl very simply and expeditiously and that the seat and cover may be turned together about the axis of the pins 9 in an upward direction or the seat alone may be turned upwardly about the axis of the pins 16.

65 This construction of hinge is particularly practical and economical to make. The hinge members are very easily fabricated at low cost. The invention is defined in the appended claims and is to be considered comprehensive of all forms of structure coming within 70 their scope.

I claim:

1. A hinge comprising, a supporting post having a head with a lateral opening in a side 90 thereof, a hinge member including an intermediate vertical section, a horizontal pin at the lower end thereof to enter the opening in said head, a horizontal forwardly extending section at the upper end of the vertical section 95 and an upwardly extending head at the forward end of said horizontal section having a lateral opening therein, and a hinge pin provided with an annular outwardly extending collar a short distance from one end thereof, 100

said hinge pin being received in the opening of the last mentioned head at one end thereof with the collar lying against a side of the head.

5. 2. In combination, a horizontal support, two posts attached to said support having heads at their upper ends each with a lateral opening therein, said heads being located above the support, a hinge member pivotally mounted on each head having a lateral pin at its lower end received in the opening of the head and a section extending upwardly and outwardly in a vertical plane from said pin and thence extending forwardly in a horizontal plane to provide a second horizontal section terminating at the forward end thereof in a vertical head having a lateral opening at the inner side thereof, a seat against the rear edge and the upper side of which said vertical and horizontal sections of the hinge members engage, means passing through said sections of the hinge member into said seat, and a cover located between the upstanding heads of said hinge members and pivotally mounted on and between the same and having pivots received in the openings in said heads.

3. A hinge comprising, a vertical post having a head at its upper end, said head having a lateral opening in one side thereof, a hinge member including an upper horizontal section terminating at its forward end in a vertically extending head and having a downwardly and inwardly extending section located substantially in a vertical plane integrally connected therewith at its rear end, the lower end of said last named section having a laterally extending pin adapted to be freely and detachably received in the opening in said head of the post, the head at the front end of said horizontal section of the hinge member having a lateral opening therein.

4. The combination with a toilet bowl, and a seat and cover therefor, of a hinge plate comprising a vertical portion located at the rear edge of said seat, a horizontal portion extending forward from the upper end of said vertical portion and located against the upper surface of said seat, an upwardly turned portion at the forward end of said horizontal portion, and means at said upwardly turned portion and at the lower end of the vertical portion for pivotal connection to said cover and bowl respectively.

5. The combination with a toilet bowl, and a seat and cover therefor, of a hinge plate comprising a vertical portion located at the rear edge of said seat, a horizontal portion extending forward from the upper end of said vertical portion and located against the upper surface of said seat, an upwardly turned portion at the forward end of said horizontal portion having an opening therein, a hinge pin on said cover extending into said opening on the upturned portion for piv-

otal connection, a head attached to said bowl having an opening therein and a pin at the lower end of the vertical portion of the hinge plate extending into the opening of the head for pivotal connection.

In testimony whereof I affix my signature.

PAUL A. JOHNSON.
